REFRIGERATING MACHINE

Christian Steenstrup, Schenectady, N. Y., assignor
to General Electric Company, a corporation of
New York

Application December 1, 1937, Serial No. 177,495

9 Claims. (Cl. 62—116)

My invention relates to refrigerating machines and particularly to such machines having cooling units arranged to provide a plurality of zones operating at different temperatures.

5 Refrigerating machines, and particularly household refrigerators, are commonly provided with evaporators which are designed to provide adequate surface to cool the air in the cabinet and also a low temperature zone in which water, deserts, and the like may be frozen. Some evaporators for this purpose have been designed to have separate sections in which the refrigerant is maintained at different pressures in order that the evaporator may inherently provide different 10 temperature zones. The freezing zone is frequently separated from the air cooling zone by insulated walls or other means in order that the air in the food compartment may not circulate through the freezing zone where a substantial 15 quantity of moisture would be removed from the air. The rate of dehydration of food in the refrigerator cabinet is minimized since the cabinet evaporator may be maintained at temperatures well above the freezing zone. It sometimes is de- 20 sirable to provide more than two different temperature zones since some foods, such as meats, are better preserved at temperatures intermediate 25 the temperature of the food compartment and that of the freezing chamber. Accordingly, it is 30 an object of my invention to provide a refrigerating machine having an improved cooling unit for establishing a plurality of cooling zones in a refrigerator cabinet.

Another object of my invention is to provide a 35 refrigerating machine including an evaporator having a plurality of sections and an improved arrangement for maintaining each of said sections at a different temperature.

A further object of my invention is to provide 40 an evaporator of the flooded type for maintaining a plurality of different temperatures and having an improved arrangement for circulating refrigerant therein.

Further objects and advantages of my invention 45 will become apparent as the following description proceeds, and the features of novelty which characterize my invention will be pointed out with particularity in the claims annexed to and forming a part of this specification.

50 For a better understanding of my invention, reference may be had to the accompanying drawings in which Fig. 1 is a front elevation of the upper portion of a household refrigerating machine embodying my invention; Fig. 2 is an en- 55 larged sectional view of the evaporator shown in

Fig. 1 taken on the line 2—2; Fig. 3 is an enlarged perspective view of the evaporator shown in Fig. 1 with the freezing chamber thereof shown removed therefrom; Fig. 4 is an enlarged sectional view of the pressure regulating valve of the 5 evaporator shown in Figs. 1 to 3; Fig. 5 is a perspective view of a modified form of an evaporator embodying my invention shown with the control panel and freezing portion removed; Fig. 6 is a 10 sectional view on the line 6—6 of Fig. 5, the 15 evaporator being shown assembled; and Fig. 7 is an enlarged view of the pressure controlling valve of the evaporator shown in Figs. 5 and 6.

Referring now to the drawings, in Fig. 1 I have 20 shown a refrigerating machine including a cabinet 10 having a food compartment 11 normally closed by a door (not shown) and a cooling unit 12 arranged within the compartment 11. A condensing unit comprising a closed casing 13 within which is arranged a motor and compressor and a 25 condenser 14 having a refrigerant conduit 15 mounted on a removable top 16 of the cabinet 10. Gaseous refrigerant is compressed by the compressor within the casing 13 and discharged into the conduit 15 where it is cooled and liquefied 30 by the natural circulation of air over the conduit, the liquid refrigerant flowing through a connection 17 into a receiver or float valve chamber 18. When a predetermined quantity of liquid refrigerant has collected in the chamber 18, a float 35 therein rises and the liquid refrigerant flows through a pair of conduits 19 to the cooling unit 12. The liquid refrigerant within the cooling unit 12 is vaporized by the absorption of heat from the air within the compartment 11 and from articles 40 placed within the cooling unit, and the vaporized refrigerant is withdrawn through a suction line 20 and returned to the casing 13. The refrigerating machine is provided with a control mechanism 21 having a thermostatic element 22 secured 45 adjacent the outer portion of the cooling unit 12, the motor within the casing 13 being started and stopped by the control mechanism 21 in response to the temperature of the thermostatic element 22. The refrigerating machine thereby maintains 50 the outer portion of the cooling unit 12 within a predetermined range of temperature. The range of temperature may be selected so that the outer evaporator rises to a temperature above freezing during each cycle and thus prevents the formation 55 of any substantial quantity of frost. This is known as the "defrosting cycle." The outer evaporator may be maintained above freezing at all times, if desired.

The cooling unit 12 as shown in Figs. 1, 2 and 3 55

comprises an outer refrigerated portion or evaporator constituting a closed chamber and comprising a housing formed by inner and outer complementary sheets of metal 23 and 24 and a bottom sheet 25 and divided into two sections by a horizontal partition 26 near the middle thereof. The upper and lower sections thus formed are closed at the front by doors 27 and 28 respectively and the upper section is closed at its top by the top wall of the food compartment. The housing is suspended from the top wall of the food compartment 11 on flanges 7, 8 and 9 formed one on each of the three walls of the housing.

In order to cool the air within the food compartment 11 and within the upper and lower sections of the cooling unit, I provide headers 29, 30 and 31 in the upper portions of the three walls of the housing and refrigerant circulating conduits 32, 33 and 34 communicating with and depending from the headers 29, 30 and 31 respectively, and extending above and below the partition 26. The headers 29, 30 and 31 are designed to be maintained substantially half filled with liquid refrigerant and they communicate with each other above and below the level of liquid refrigerant at the corners of the walls, the three headers as shown being formed as a continuous header around the three sides of the housing. The several refrigerant circulating passages and headers are formed as indentations in the sheet 23 while the sheets are flat. The sheets are then secured together by welding or brazing or any other suitable manner around their edges and around the indentations and are then bent to form the three-sided housing. In order to supply liquid refrigerant to the cooling unit 12 and to produce a circulation of liquid refrigerant, I connect the supply lines 19 so that they inject refrigerant into the passages 33 and 34 and produce a circulation of refrigerant therein. In order to increase the area of the cooled surface of the evaporator unit, I provide a plurality of fins 35 formed of channel-shaped members secured to the outer surface of the three walls of the housing.

In order to constitute the upper section a freezing chamber or compartment, I provide an evaporator comprising upper and lower refrigerated shelves 36 and 37 spaced apart and secured on brackets 38 and 39 within an open ended rectangular casing 40. The shelves 36 and 37 are provided with headers 41 and 42 respectively, and a plurality of refrigerant passages communicating therewith. The arrangement of the passages in the two shelves is the same and can be seen from the illustration of the lower shelf 37. A U-shaped passage 43 is provided extending around the sides of the shelf 37 and communicating at its two ends with the ends of the header 42 and two smaller U-shaped passages 44 are arranged within the shelf inside the area enclosed by the passage 43 and ducts 45 are provided at the midpoints of the passages 44 to provide communication between the passage 43 and the passages 44. In order to provide an adequate circulation of liquid refrigerant through the passages of the shelves, I inject refrigerant into the outer U-shaped passages of the two shelves through refrigerant supply injectors 46 and 47 of the upper and lower shelves respectively. A portion of the outer U-shaped passage of the upper shelf 36 can be seen in Fig. 3 as indicated at 48. Refrigerant is supplied to the shelf evaporators in sufficient quantity to maintain the shelves flooded, the liquid refrigerant normally half filling the headers 41 and 42.

The headers 41 and 42 are maintained in communication through a tube 49 which is arranged to remove vaporized refrigerant from the header 42 above the liquid level and extends above the liquid level in the header 41. The suction line 20 is connected to the upper header 29 as shown, and removes vaporized refrigerant from the header 41. The shelf evaporator casing 40 is mounted within the upper section of the cooling unit 12 on the spacers 50, so that the walls of the casing 40 are spaced from the walls of the outer housing and form the partition 26. This, in effect, provides an insulating air space between the freezing chamber and the food compartment 11 and between the upper and lower sections of the housing thus partially insulating the sections and limiting the transfer of heat from the lower section to the upper section. In order to maintain the shelves 36 and 37 at sharp freezing temperatures, and the outer walls of the casing at temperatures required for a defrosting cycle or above freezing, I provide a pressure reducing valve 51 in a refrigerant connection 52 which communicates with the header 30 and with the injectors 46 and 47, and provides a passage for refrigerant between the evaporators. The connection 52 opens into the header 30 near the normal level of liquid refrigerant therein. Therefore, when gaseous refrigerant is withdrawn from the header through the connection, any excess liquid refrigerant is withdrawn therewith and both liquid and gaseous refrigerant flow from the header through the valve 51 into the inner evaporator. The degree of opening of the valve 51 may be varied by turning a handle 53. It will be evident that the outer evaporator comprising the conduits and headers formed on the outer housing may be maintained at a different pressure than the inner evaporator comprising conduits and headers of the shelves within the inner casing by restricting the passage of refrigerant between the two evaporators. Since the refrigerant is first admitted to the outer evaporator, thence flows through the valve 51 to the inner evaporator and is withdrawn from the inner evaporator by the compressor, the inner evaporator will be maintained at a lower pressure than the outer evaporator and hence at a lower temperature, the difference in temperature being determined by the setting of the valve 51. Since the refrigerating machine is controlled in response to the temperature of the outer evaporator, that temperature will remain substantially constant and, by changing the setting of the valve 51, the pressure within the inner evaporator and, hence, the temperature and rate of freezing of fluids placed therein can be regulated as desired. The construction of the valve 51 is clearly shown in Fig. 4 in which I have shown a sectional view. A needle valve 54 is arranged to seat in an opening 55, the position of the valve with respect to the opening being adjusted by the handle 53, so that any desired degree of opening may be obtained. An indicating dial 56 is provided on the shaft of the handle 53 to indicate the position of the valve 54, a stationary pointer 57 cooperating with the dial 56. The dial 56 may be calibrated in any suitable manner in order to indicate the relative temperatures of the evaporators.

I have found it desirable to provide an arrangement to prevent the complete shutting off of communication between the inner and outer evaporators, so that there is always some degree of refrigeration in the outer evaporator even though the differential temperature is set at its highest value. I, therefore, provide a small by-

pass opening 58 around the valve opening 55 so that there must be at least a minimum opening at all times providing at least a restricted measure of communication between the conduits 5 of the outer evaporator and the freezing shelves. The size of the opening 58 should be selected so that the outer evaporator will not rise above a predetermined desired temperature even though the evaporators are working at the 10 greatest differential of pressure. It will be understood readily by those skilled in the art that if the valve 51 is permitted to shut off entirely the flow of refrigerant between the evaporators, then the temperature of the outer evaporator 15 would rise and continuously call for cooling, thereby reducing the pressure within the inner evaporator to a minimum without reducing the pressure in the outer evaporator. This condition is obviously undesirable since the temperature of the outer evaporator and, hence, the 20 temperature of the food compartment could not be controlled during the freezing period.

During the operation of the refrigerating machine shown in Fig. 1, the temperature of the outer walls of the cooling unit 12 will be regulated by the control device 21 and the refrigerating machine will operate to remove refrigerant from the inner evaporator to maintain a lower temperature therein as determined by the setting 30 of the valve 51. The doors 27 and 28 prevent the circulation of air from the food compartment over the colder portions of the cooling unit and, therefore, minimize the dehydration of air and food within the cabinet. The lower section 35 of the cooling unit closed by the door 28 is maintained at a lower temperature than the air within the cabinet 11 since it is arranged intermediate the cabinet 11 and the freezing chamber. The refrigerating effect of the lower portions of the 40 coils 32, 33 and 34 maintain the small amount of air within the lower section at a relatively low temperature as compared with the temperature of the cabinet air surrounding the cooling unit, but not as low a temperature as that maintained 45 in the upper section of the housing by operation of the freezing shelves therein. During normal operation of a refrigerating machine such as that illustrated, the cabinet air might be maintained within a range of temperatures between 45 and 50° F. and the freezing chamber or compartment 50 within a suitable range of temperatures below freezing. The range of temperatures maintained within the lower section of the housing may vary between 35 and 45° F., which is a suitable 55 range for the preservation of such foods as meats.

In Figs. 5, 6 and 7, I have shown a cooling unit embodying a modified form of my invention. This cooling unit may be arranged within a 60 cabinet of a refrigerating machine in the same manner as the cooling unit shown in Fig. 1. The cooling unit comprises an outer housing formed of inner and outer complementary metal sheets 69 and 60 respectively, and comprising three walls 65 forming the sides and back wall of the cooling unit, flanges 61, 62 and 63 are formed at the tops 70 of the walls to support the unit within a refrigerator cabinet in such a manner as to hold the top of the unit against the top wall of a food compartment. The bottom side of the housing is closed by wall 64 and a partition comprising two walls 65 and 66 is provided to divide the housing into an upper and a lower section, the walls 65 and 66 forming a dead air space between the sections to limit the flow of heat from

the lower section to the upper section. The upper section may be closed by a door 67 and the lower section by a door 68, the doors being shown only in Fig. 6. In order to refrigerate the side walls of the housing, I provide headers 69, 5 70 and 71 formed by complementary indentations in the inner and outer sheets 59 and 60, the headers 69 and 70 being maintained about half full of liquid refrigerant and connected above the normal liquid level therein by a passage 10 72 and below the normal liquid level by a passage 13. The headers 70 and 71 are connected by similar passages 74 and 75 above and below the liquid level respectively. In order to circulate liquid refrigerant in the wall on the side in which 15 is formed the header 69, I provide substantially vertical passages 76 and 77 formed in the outer sheet 60 and communicating at their upper ends with the header 69 and a plurality of substantially parallel inclined transverse passages 78 20 formed in the inner sheet 59 and extending from the passage 76 to the passage 77. The ends of the passages 78 communicate with the passage 76 at a higher level than the ends communicating with the passage 77, which produces a 25 tendency for refrigerant vaporized in the passages 78 to flow into the passage 76 and thereby produce some natural circulation of refrigerant from the passage 77 to the passage 76. In order to induce a positive circulation in the passages 30 78, I inject refrigerant upwardly into the passage 76 in the bottom thereof through an injector 79. This produces a rapid upward circulation of refrigerant in the passages 76 and induces a flow of refrigerant through the passages 78 toward the passage 76 and thence to the 35 header 69, the liquid refrigerant returning to the passages 78 through the passage 77. The walls below the headers 70 and 71 are provided with similar refrigerant passages, the similar passages 40 in the back wall communicating with the header 70 being designated by the same numerals with the addition of the letter *a*, and the similar 45 passages communicating with the header 71 in the other side wall being designated by the same numerals with the addition of the letter *b*. Liquid refrigerant is admitted to the cooling unit through liquid line 80 which corresponds to the 50 double liquid lines 19 shown in Fig. 1. The liquid refrigerant flows from the line 80 into a manifold 81 formed in the outer sheet 60 and substantially parallel to the transverse passages 78, 78a, and 78b, and the injector ducts 79, 79a, and 79b connect the manifold 81 with the upright 55 passages 76, 78a, and 78b respectively, and thereby produce a circulation of refrigerant on all three sides of the housing.

The several passages and the headers in the sheets 59 and 60 are formed while the sheets are flat. The sheets are then secured together 60 by welding or brazing or in any other suitable manner around the edges, and between the indentations, and are then bent to form the three sided housing as shown. It will be evident that 65 since the passages 78, 78a and 78b are arranged in alignment and on the opposite side of the structure from the upright passages, the sheets 59 and 60 may be secured together by line welds formed along the sides of the passages 78, 78a and 78b by a welding wheel which may traverse 70 the three walls of the evaporator without being lifted from the sheet 59. The construction of the evaporator is, therefore, simplified by forming the passages 78, 78a and 78b in the inner sheet 59 while the upright passages are formed 75

in the outer sheet 60. Furthermore, the inner sheet has no vertical indentations which would interfere with the partitions 65 and 66 and require the partitions to be cut to conform to the wall, and also a plurality of straight fins 82 similar to the fins 35 on the evaporator shown in Fig. 3 may be secured on the outer sheet 60 which is free from any transverse irregularities since the transverse passages 78, 78a and 78b are located on the inner side of the walls.

The construction and arrangement of the evaporator constituting the outer housing disclosed in Figs. 5, 6 and 7 is described and claimed in my copending application Serial No. 285,702, filed July 21, 1939, which is a division of my present application.

In order to provide freezing capacity, an evaporator 83 is arranged within the upper section of the housing as shown in Fig. 6, the evaporator 83 being shown removed from the housing in Fig. 5. This evaporator may be of any suitable form. However, I prefer to use an evaporator of the type shown and described in application Serial No. 51,846, filed November 27, 1935, in the name of Leonard W. Atchison, and assigned to the General Electric Company, assignee of my present invention. The evaporator 83 comprises a header 84 formed between inner and outer complementary sheets 85 and 86. A plurality of passages 87 open into the header 84 at their upper ends and extend downwardly over a side wall below the header and over the bottom wall of the evaporator. Liquid and gaseous refrigerant is admitted to the evaporator through a connection 88 and flows through a series conduit 89, portions of which are shown in Fig. 5 on the side wall of the evaporator opposite the header. From the conduit 89, the liquid and vaporized refrigerant flows through a manifold 40 (not shown) into the conduits 87 to produce a circulation of refrigerant in the conduits 87. A dummy wall or extension 90 is provided to enclose an upper compartment of the evaporator 83 and also provide a flange 91 which cooperates with a flange 92 above the header 84 to provide a support, whereby the evaporator 83 may be secured to the top wall of the refrigerator cabinet. The series conduit 89 extends over the area of a shelf 93 and evaporator 83 therefore provides 50 two freezing shelves and constitutes a freezing chamber. When the evaporator 83 is mounted within the upper section of the housing of the cooling unit, the walls of the evaporator are spaced from the walls of the housing and from 55 the partition 66. Liquid or gaseous refrigerant flows from the header 70 through a connection 94 and an adjustable throttling valve 95 to the connection 88 and thence into the evaporator 83. The connection 94 opens into the header 70 near 60 the normal level of liquid refrigerant therein and both liquid and gaseous refrigerant are, therefore, withdrawn from the header 70 in the same manner as from the header 30 of the evaporator shown in Fig. 2. Gaseous refrigerant is withdrawn 65 from the header 84 above the level of liquid refrigerant and hence from the cooling unit through a suction line 96 corresponding to the suction line 20 shown in Fig. 1. The valve 95 is mounted in a U-shaped bracket 97 which 70 is secured to a cross panel 98 mounted in the upper front portion of the cooling unit as indicated in Fig. 6, the panel being shown removed in Fig. 5.

The construction of the valve 95 is clearly shown in Fig. 7, where I have indicated the valve

bracket 97 secured by screws 99 to the panel 98. The valve 95 is similar to the valve 51 shown in Fig. 4 in that an arrangement is provided so that the valve may not be closed entirely and at least a minimum flow of refrigerant is afforded at all times. Valve 95 comprises a valve block 100 secured in the bracket 97 by a threaded connection 101 and a nut 102. The connections 88 and 94 communicate with a passage 103 within the valve block and a valve stem or plunger 104 is provided to vary the opening of the valve, the limiting position of the stem being determined by shoulder 105 which maintains open a passage 106, so that the valve cannot be closed completely. The valve stem 104 is sealed against leakage by an expandable bellows 107, which maintains the seal during the axial movement of the stem. The valve may be adjusted by movement of a cam 108 against which a head 109 of the valve stem is pressed by a spring 110 within the bellows 107. The cam 108 is mounted in the end of the bracket 97 and may be rotated by a knob 111 having a pointer 112 to indicate the position of the valve. In Fig. 7, the valve is shown in its position of maximum opening. It is evident that the position of the valve stem 104 may easily be adjusted by turning the knob 111 and there is no danger of leakage or loss of refrigerant since the bellows 107 maintains the valve sealed.

During the operation of the unit shown in Figs. 5, 6 and 7, refrigerant is admitted to the cooling unit through the liquid line 80 and flows into the walls of the outer housing through the manifold 81 and ducts 79, 79a and 79b which produces a circulation of refrigerant in the transverse conduits 78, 78a and 78b and cools the air within the food compartment and also within the upper and lower sections of the housing. Liquid and gaseous refrigerant then flows through the connection 94 and the valve 95 to the inner evaporator 83 which constitutes the upper section of the housing a freezing compartment in which sufficiently low temperatures are maintained for the freezing of water, desserts and the like. The gaseous refrigerant is discharged from the cooling unit through connection 96 and returned to the refrigerating machine in the same manner as was described with regard to the cooling unit shown in Fig. 1. Valve 95 maintains a differential of pressure between the inner and outer evaporators in the same manner as the valve 51 of Figs. 1 to 4 inclusive, and the lower section of the housing of the cooling unit is maintained at a temperature intermediate the temperatures of the freezing chamber and food compartment in the same manner as the temperature is maintained in the lower compartment of the cooling unit shown in Fig. 1.

Both of the cooling units described above are preferably arranged within a refrigerator cabinet so that they are spaced from the side and back walls thereof and afford a free circulation of the air of the food compartment over the evaporator. The large cooling area thus provided, makes it possible to operate the outer portion of the evaporator at much higher temperatures than are required to maintain the desired air temperatures with a small evaporator surface. The doors provided for the cooling units prevent the circulation of the food compartment air over the intensely cooled portions of the cooling unit and thereby reduce to a minimum, the dehydration of food and air contained in the main food compartment. Meats and similar comestibles are

kept for substantially longer periods in the lower portions of the cooling units constructed as shown, and are not subject to dehydration and discoloration which results when these foods are placed in higher temperature compartments, such as the main food compartment. In both the modifications illustrated, the refrigerating machine is preferably controlled by a thermostatic element such as the element 22 shown in Fig. 1 secured in the main wall of the housing of the cooling unit, so that the operation of the refrigerating machine is controlled in response to the temperature of the higher pressure evaporator. The valves shown in Figs. 4 and 7 may easily be adjusted to maintain the desired difference of temperatures and are so constructed that some refrigerating capacity is available in both evaporators of the cooling unit at all times.

While I have shown particular embodiments of my invention in connection with a household refrigerating machine, other modifications will readily be apparent to those skilled in the art. I do not, therefore, desire my invention to be limited to the constructions shown and described, and I intend in the appended claims to cover all modifications within the spirit and scope of my invention.

What I claim as new and desire to secure by Letters Patent of the United States, is:

1. A refrigerating machine including a cabinet having a food compartment to be cooled, a cooling unit arranged within said compartment, said cooling unit comprising a housing forming a closed chamber, means for dividing said chamber into a plurality of sections and for partially insulating two of said sections from each other, means including a refrigerant conduit arranged on the walls of said housing for cooling the air within said food compartment and for cooling the walls of said two of said sections, means associated with one of said two sections for constituting said one of said two sections a freezing chamber, said last-mentioned means including a freezing shelf adapted to contain refrigerant means for supplying refrigerant to said conduit and to said shelf and for withdrawing refrigerant therefrom, and means for maintaining a higher pressure of refrigerant in said conduit than in said shelf whereby the other of said two sections is maintained at a temperature intermediate that of said food compartment and that of said freezing chamber.

2. A refrigerating machine including a cabinet having a food compartment to be cooled, a cooling unit arranged within said food compartment, said cooling unit comprising a housing forming a closed chamber, means for dividing said chamber into a plurality of sections and for partially insulating two of said sections from each other, means including a refrigerant conduit arranged on the walls of said housing for cooling the air within said food compartment and for cooling the walls of said two of said sections, means associated with one of said two sections for constituting said one of said two sections a freezing chamber, said last-mentioned means including a shelf adapted to contain refrigerant, means for supplying refrigerant to said conduit and to said shelf and for withdrawing refrigerant therefrom, and means for maintaining said conduit at a higher temperature than said freezing shelf whereby the other of said two sections is maintained at a temperature intermediate that of said food compartment and that of said freezing chamber.

3. A refrigerating machine including a cabinet having a food compartment to be cooled, a cooling unit arranged within said food compartment, said cooling unit comprising a housing forming a closed chamber, means including a refrigerant conduit arranged on the walls of said housing for cooling the air within said compartment and for cooling the walls of said chamber, means including a refrigerant evaporator for dividing said chamber into at least two sections partially insulated from one another and for providing a freezing chamber in one of said sections, means for supplying refrigerant to said conduit and to said evaporator and for withdrawing refrigerant therefrom, and means for maintaining said conduit at a higher temperature than said evaporator whereby the other of said two sections is maintained at a temperature intermediate that of said food compartment and that of said freezing chamber.

4. A refrigerating machine including a cabinet having a food compartment to be cooled, a cooling unit arranged within said food compartment, said cooling unit including a wall having a refrigerant conduit arranged thereon for cooling the air within said food compartment, means including a freezing shelf adapted to contain refrigerant for providing a freezing surface, means connecting said refrigerant conduit and said freezing shelf for conveying refrigerant from said conduit to said shelf, means for supplying refrigerant to said cooling unit and for withdrawing refrigerant from said freezing shelf, means including an adjustable valve arranged in said connecting means for maintaining said conduit at a higher temperature than said shelf, and means for affording at least a restricted measure of communication between said conduit and said shelf at all times.

5. A refrigerating machine including a cabinet having a food compartment to be cooled, a cooling unit arranged within said food compartment, said cooling unit comprising a housing forming a closed chamber, means for dividing said chamber into a plurality of sections, means including a refrigerant conduit arranged on the walls of said housing for cooling the air within said food compartment and for cooling the walls of two of said sections, means associated with one of said two sections for constituting said one of said two sections a freezing chamber, said last-mentioned means including a freezing shelf adapted to contain refrigerant, means connecting said refrigerant conduit and said freezing shelf for conveying refrigerant from said conduit to said shelf, means for supplying refrigerant to said cooling unit and for withdrawing refrigerant therefrom, means including an adjustable valve arranged in said connecting means for maintaining said conduit at a higher temperature than said shelf, and means for affording at least a restricted measure of communication between said conduit and said shelf at all times.

6. A refrigerating machine including a cabinet having a food compartment to be cooled, a condensing unit for supplying refrigerant, means including a cooling wall connected to receive refrigerant from said condensing unit and having a refrigerant conduit for cooling said food compartment, means including a freezing shelf adapted to contain refrigerant for providing a freezing chamber for said refrigerating machine, means connecting said refrigerant conduit and said freezing shelf for conveying refrigerant from said conduit to said shelf, means including a

- valve arranged in said connecting means for maintaining said conduit at a higher temperature than said freezing shelf, said valve including a valve block having a valve stem slidably mounted therein and an expandible bellows for sealing said valve against leakage of refrigerant, means including a cam for adjusting the position of said valve stem to vary the relative pressures in said refrigerant conduit and said freezing shelf, means for maintaining said valve partially open at all times, and means for returning to said condensing unit refrigerant vaporized in said cooling wall.
7. A refrigerating machine including a cabinet having a food compartment to be cooled, a cooling unit arranged within said food compartment, said cooling unit comprising a housing forming a closed chamber, means for dividing said chamber into a plurality of sections and for partially insulating two of said sections from each other, means including a refrigerant conduit arranged on the walls of said housing for cooling the air within said food compartment and for cooling the walls of said two of said sections, means including a freezing chamber having walls adapted to contain refrigerant and arranged in one of said two sections for constituting said one section a freezing compartment, the walls of said freezing chamber being spaced from the walls of said one section, means for supplying refrigerant to said conduit and to said walls of said freezing chamber and for withdrawing refrigerant therefrom, and means for maintaining said conduit at a higher temperature than the walls of said freezing chamber whereby the other of said two sections is maintained at a temperature intermediate that of said food compartment and that of said freezing compartment.
8. A cooling unit for refrigerating machines comprising a housing forming a closed chamber, means for dividing said chamber into a plurality of sections, a refrigerant conduit arranged on the walls of said housing for cooling the air sur-
- rounding said housing and for cooling the walls of two of said sections, means associated with one of said two sections for constituting said one of said two sections a freezing chamber, said last-mentioned means including a freezing shelf partially insulated from the other of said two sections and adapted to contain refrigerant, an inlet connection for conducting refrigerant to said conduit and an outlet connection for conveying refrigerant withdrawn from said cooling unit, and means adapted to cooperate with the condensing unit of a refrigerating machine for maintaining said conduit at a higher temperature than said freezing shelf whereby the other of said two sections is maintained at a temperature intermediate that of the freezing chamber and of the air surrounding said housing.
9. A cooling unit for refrigerating machines comprising a housing forming a closed chamber, means for dividing said chamber into a plurality of sections, means including a refrigerant conduit of the flooded type arranged on the walls of said housing for cooling the air surrounding said housing and for cooling the walls of two of said sections, means associated with one of said two sections for constituting said one of said two sections a freezing chamber, said last-mentioned means including a freezing shelf adapted to contain refrigerant, means connecting said conduit and said freezing shelf for conveying refrigerant to said shelf, an inlet connection for conducting refrigerant to said cooling unit and an outlet connection for conveying refrigerant withdrawn from said cooling unit, means including an adjustable valve arranged in said connecting means adapted to cooperate with the condensing unit of a refrigerating machine for maintaining said conduit at a higher temperature than said shelf, and means for affording at least a restricted measure of communication between said conduit and said shelf at all times.

CHRISTIAN STEENSTRUP.

CERTIFICATE OF CORRECTION.

Patent No. 2,234,711.

March 11, 1941.

CHRISTIAN STEENSTRUP.

It is hereby certified that error appears in the printed specification of the above numbered patent requiring correction as follows: Page 3, second column, line 43, for "letter d" read --letter a--; page 5, first column, line 44, claim 1, after the word "refrigerant" insert a comma; and that the said Letters Patent should be read with this correction therein that the same may conform to the record of the case in the Patent Office.

Signed and sealed this 15th day of April, A. D. 1941.

Henry Van Arsdale,
Acting Commissioner of Patents.
